United States Patent Office

Des. 203,915
Patented Feb. 22, 1966

203,915

PIPE CADDY

Reuben G. Thoreen, 522 S. Broadway St., Stillwater, Minn., and Mather Garland, 17238 Clear Spring Lane, Minnetonka, Minn.

Filed Mar. 30, 1965, Ser. No. 84,523

Term of patent 14 years

(Cl. D85—8)

FIGURE 1 is a perspective view of a pipe caddy embodying our new design;

FIGURE 2 is a top plan view;

FIGURE 3 is a front elevational view;

FIGURE 4 is a bottom view;

FIGURE 5 is an end elevational view looking from the right of FIGURE 1; and

FIGURE 6 is an end elevational view looking from the left of FIGURE 1.

We claim:

The ornamental design for a pipe caddy, as shown.
